UNITED STATES PATENT OFFICE.

HAROLD C. EDDY, OF LOS ANGELES, CALIFORNIA, ASSIGNOR TO PETROLEUM RECTIFYING COMPANY OF CALIFORNIA, OF SAN FRANCISCO, CALIFORNIA, A CORPORATION OF CALIFORNIA.

ADJUSTABLE FIELD DEHYDRATOR.

Application filed June 25, 1921. Serial No. 480,349.

To all whom it may concern:

Be it known that I, HAROLD C. EDDY, a citizen of the United States, residing at Los Angeles, in the county of Los Angeles and 5 State of California, have invented a new and useful Adjustable Field Dehydrator, of which the following is a specification.

My invention relates to dehydrators and particularly to dehydrators which are 10 adapted to remove water from petroleum oils by the use of an electric field.

It is a well known fact that if petroleum emulsions are subjected to an electric field that the fine water particles of the emulsion 15 tend to agglomerate into larger masses which may be readily settled out by gravity.

The principal object of my invention is to provide a dehydrator in which the electric field is adjustable.

20 A further object of my invention is to provide means in such an adjustable dehydrator for preventing the persistence of the water chains ordinarily formed in such a dehydrator.

25 A further object of my invention is to provide a dehydrator of the above described characteristics which will be mechanically very simple.

Referring to the drawing which is for 30 illustrative purposes only,

Fig. 1 is a section through a preferred embodiment of my invention.

Fig. 2 is a section on a plane represented by the line 2-2 of Fig. 1.

35 In the form of the invention shown, 11 is a tank provided with an inlet pipe 17 and an outlet pipe 18, the outlet pipe being carried to a T 19, and vented as shown at 20 to maintain a constant supply of fluid in the tank 11. Mounted on brackets 25 and insulators 26 is a platform 27 carrying bearings 28 in which a shaft 29 is free to turn. This shaft is provided with a crank 30 connected through a link 31 with a crank 32 40 carried on a shaft 33. The shaft 33 is driven by a pulley 34 by means of a rubber or other insulating belt 35 from motor 36. Suspended on arms 40 from the shaft 29 is a flat plate 41 which forms the moving electrode of the system. Carried inside the tank 11 are two plates 50, each of these plates being carried on four bolts 51 which are engaged by a nut 52 having a hand wheel 53.

50 The nut 52 is axially restrained by a casting

54 being free to turn in that casting. A 55 transformer 60 having a low voltage primary 61 and a high voltage secondary 62 is provided, the secondary 62 being connected through a wire 63 with a platform 27 and hence with the moving electrode 41, the other 60 side of the secondary being connected through a wire 64 with the tank 11 and hence with the plates 50.

The method of operation of the invention 65 is as follows:

The emulsion being delivered through the pipe 17 to the interior of the tank, this tank is filled to the level of the T 19 with such emulsion. The motor 36 being started, the crank 32 revolves and oscillates the crank 30 70 through the link 31 due to the fact that the crank 30 is considerably longer than the crank 32. The oscillation of the crank 30 moves the moving electrode 41 from the position shown in full lines in Fig. 1 into the 75 position shown in dotted lines in that figure. In other words, the moving electrode 41 moves back and forth inside the tank in its own plane cutting the liquid just as a knife would cut it. This movement of the electrode is accomplished therefor with a minimum agitation or disturbance of the emulsion. The secondary 62 sets up an intense 80 electric field between the plate 41 and the plates 50 and this field tends to establish 85 water conducting chains between the plates. The movement of the plate 41 tends to prevent these chains from persisting.

An important feature of my invention is the fact that the distance between plates 41 90 and the plates 50 can be adjusted by turning the hand wheels 53 which moves the plates 50 in and out. It is possible that while the apparatus is running to adjust these plates 95 so that the length of the field can be readily changed to suit the particular type of emulsion being treated. As electrode 41 swings to its extreme positions, a field is established for a few seconds between the edge of the electrode 41 and the end of the tank 11, 100 changing from one end to the other as the electrode swings.

I claim as my invention:

1. In a dehydrator, the combination of: a moving electrode formed of a flat plate; and means for moving said plate in its own plane.
2. In a dehydrator, the combination of: a moving electrode formed of a flat plate; and

means for oscillating said plate in its own plane.

3. In a dehydrator, the combination of: a moving electrode; a stationary electrode parallel to said moving electrode; and means for adjusting the distance between said electrodes.

4. In a dehydrator, the combination of: a moving electrode; a stationary electrode parallel to said moving electrode; and means for adjusting the position of said stationary electrode to vary the distance between said electrodes.

5. In a dehydrator, the combination of: a moving electrode formed of a flat plate of metal; a stationary electrode parallel to said moving electrode; and means for adjusting the distance between said electrodes.

6. In a dehydrator, the combination of: a moving electrode formed of a flat plate of metal; a stationary electrode parallel to said moving electrode; and means for adjusting the distance between said electrodes.

the position of said stationary electrode to vary the distance between said electrodes.

7. In a dehydrator, the combination of: a moving electrode formed of a flat plate of metal; means for oscillating said flat plate in its own plane; a stationary electrode parallel to said moving electrode; and means for adjusting the distance between said electrodes.

8. In a dehydrator, the combination of: a moving electrode formed of a flat plate of metal; means for oscillating said flat plate in its own plane; a stationary electrode parallel to said moving electrode; and means for adjusting the position of said stationary electrode to vary the distance between said electrodes.

In testimony whereof, I have hereunto set my hand at Los Angeles, California, this 17th day of June, 1921.

HAROLD C. EDDY.
